ROTARY ROCK BIT

James W. Sperry, San Marino, Calif.

Application October 20, 1930, Serial No. 489,931

9 Claims. (Cl. 255—71)

My invention relates to drilling bits for use in boring holes in hard formations and relates particularly to roller rock bits which penetrate by the crushing action of the rollers.

5 In the oil well drilling industry roller bits now employed consist essentially of two types, the conical roller type and the cylindrical roller type, the rollers of which are provided with teeth or ridges which crush the surface portion of the formation against which the rollers are operated with a disintegrating action.

10 My invention relates to the construction of bits of this character rather than to the principles of operation, and it is an object of the invention to provide a rotary bit structure having a one-piece bit body instead of the two-piece bit body extensively used for well drilling, and it is a further object to provide a simple, yet entirely safe and practical means for securing the rollers to the 15 one-piece bit body.

20 A further object is to provide a securing means for the rollers which will not permit the rollers to become lost in the well, but which is of such character that when the bit is removed from the well, the rollers may be easily removed and re-placed or resharpened.

25 A further object of the invention is to provide a roller bit having means for keeping the teeth or grooves of the rollers clean, thereby maintaining a maximum cutting efficiency at all times during the operation of the bit.

30 It is also an object of the invention to provide a single-piece bit body and removable bearing structures for the rollers, these bearing structures being secured to the bit body by the use of interlocking or tongue and groove members so constructed that the rollers may be readily installed on and removed from the bit body.

35 Another object of the invention is to provide 40 a bearing structure which does not require lubricating systems having pressure feed oil cylinders and the like, but which may be packed with lubricant more than sufficient for a single run of the rollers.

45 A still further object of the invention is to provide a bit having protected water course channels so directed that the drilling fluid issuing therefrom will keep the rollers of the bit clean.

50 A feature of the invention is to protect these water course channels with replaceable inserts which will take the wear, prevent enlargement of the water course channels and maintain the alignment of the jets of drilling fluid with respect to the cutters, in this manner maintaining

a constant cleaning of the bit rollers by the jets of drilling fluid.

Further objects and advantages of the invention will appear throughout the following part of the specification. 5

Referring to the drawings, which are for illustrative purposes only,

Fig. 1 is a partly sectioned elevational view of a preferred embodiment of my invention.

Fig. 2 is a bottom plan view of Fig. 1 with one 10 of the rollers and its bearing structure removed.

Fig. 3 is a fragmentary sectional view showing an alternative interlocking construction.

Fig. 4 is a fragmentary sectional view showing an additional method of securing the bearing 15 structures to the bit body.

Fig. 5 is a section taken on a plane represented by the line 5—5 of Fig. 4.

Fig. 6 shows the manner in which the grooves may be placed radially instead of tangentially. 20

Fig. 7 is a fragmentary sectional view showing an alternative form of water course protector.

Referring to Figs. 1 and 2, I employ a solid or one-piece bit body 11 adapted to be secured to a string of drill pipe or drill stem 12. At the 25 lower end of the bit 11 a pair of short legs 13 are formed, these legs having diagonally directed and inwardly faced surface portions 14 adjacent which conical rollers 15 are secured. Although the angle at which the surface portions 14 are extended 30 may vary, I have found it generally advisable to place the surface portions 14 at angles of approximately 45° to the axis of rotation A—A of the bit body 11, and to make the conical rollers with an external angle of 90°. 35

As shown in Fig. 1, each conical roller 15 is supported by a bearing structure 16 having an axis B—B on which the conical roller 15 is rotatably supported. This axis B—B is preferably normal or perpendicular to the face portion 14. 40 The axes B—B, where a substantially true and rolling condition is to be attained, should intersect at a point P on the axis A—A. Each roller 15 has a conical recess 17 threaded at 18 to receive a ring 19 which holds the roller 15 on a conical bearing block 20. This conical bearing block is bored and threaded left-hand as shown at 21, to receive a threaded pin 22 having an interlocking body 23 formed on its upper end for engagement with a groove or channel 24 formed 45 in the surface portion 14. The interlocking body has upper and lower edge portions 26 and 27 which may be conveniently made of dovetail form, as shown, and the groove 24 is confined between edge walls 28 which cooperates with edge por- 50

tions of the body 23. The tongue and groove interlocking parts thus formed can be moved relative to each other only in one direction. I direct the groove 24 tangentially with respect to a circle about the axis A—A and normal to the axis B—B. A counterbored opening 30 is formed in the leg 13 to permit a locking device, such as a screw 31 to be screwed into the interlocking body 23 and the threaded pin 22 in the manner shown, thereby preventing tangential movement of the bearing structure 16, which includes parts 20 and 22, relative to the bit body 11. Adjacent to a face 33 of the conical body 20 I place a bearing ring 34 which is clamped between the conical body 20 and the interlocking body 23 when the conical body 20 is screwed on the pin 22.

The bearing structure 16 and the roller 15 are assembled before being mounted on the bit body 11. A quantity of lubricant, such as heavy grease, is placed in the recess 17 and the conical bearing body 20 is then placed in the conical recess 17 and the holding ring 19 is screwed in place so as to occupy the annular groove 36 adjacent to the upper face 33 of the conical bearing body 20. The wear ring 34 is then placed in concentric position on the face 33 and a pin 38 is caused to engage the conical body 20 and the wear ring 34 in such a manner that the holding of the wear ring will prevent rotation of the conical bearing body 20 while the pin 22 is being screwed into the threaded bore 21. When the screw 22 has been screwed in to its full extent so that the interlocking body formed thereon is in tight engagement with the wear ring 34, the interlocking body 23 is slid into the groove 24 and the locking means consisting of the screw 31 is inserted and drawn up tight.

Although the edge walls 28 of the groove 24 may be extended parallel to each other, it is preferable to cause them to converge, as shown in Fig. 2, in a direction opposite to the direction of rotation of the bit body, thereby utilizing the torque which is transmitted from the bit body to the bearing structure 16 during the operation of the bit, for the purpose of holding the interlocking body 23 and the bearing structure in tight engagement with the interlocking parts of the bit body.

As shown in Fig. 2, a single opening 30 for a locking screw 31 may be provided for each bearing structure 16 for smaller bits, but in bits of larger size it may be desirable to employ a pair of locking screws in the position indicated by dotted lines 40. The opening 30 may be made purposely larger than the screw 31 so as to permit a slight movement of the screw 31 when the interlocking body 23 is forced up tightly into the converging or tapered groove 24.

It is evident that with the pair of rollers 15 mounted in position for operation on the bit body 11 the conical bearing bodies 20 cannot be unscrewed from the pins 22, nor can the rollers 15 be removed from the conical bearing bodies. The movement between the interlocking body 23 and the groove 24 required for disengagement of the bearing structure 16 from the bit body 11 is so directed that, should the locking screw 31 be omitted or become lost in the well, movement of the interlocking body 23 in the groove 24 would result in an engagement of the forward end of the interlocking body 23 with the wall of the well and the reaction thereof during rotation of the bit would constantly tend to force the interlocking body 23 into the tapered groove 24, the result of this being that loss in

the well of any part of the bit structure, other than the screw 31 and its locking nut, is practically impossible. My simple tongue and groove means for securing the bearing structures to the bit body 11 contributes to that feature of the invention relating to a one-piece bit body. The bit body, avoiding the use of a number of parts secured together by screws, is rigid, entirely safe to operate, and relatively economical in production.

For securing the bit body to the drill pipe 12, I provide a threaded opening 45, and leading downwardly from the bottom 46 of the opening 45 are water course channels 47 and 48 directed respectively toward the right and left-hand rollers 15 so that the streams of drilling fluid issuing therefrom will travel through the surface slots 49 of the cutters and keep same washed clean from accumulations of cuttings. The openings 47 and 48 are protected by wear resistant liners 51 which project downwardly from a circular plate 52. The liners 51 and the plate 52 are preferably made from a rubber compound which will resist wear from abrasive particles carried in the drilling fluid and will protect the walls of the openings 47 and 48 so that they will not become disaligned or enlarged.

In Fig. 3 I show one leg 13' of a bit body 11' having a groove 24' therein of double dovetail form for receiving an interlocking body 23' of double dovetail form, the purpose of this view being to indicate that the interlocking parts for holding the bearing structure to the bit body may be any one of a number of forms.

In Figs. 4 and 5 I show a different manner of placing the locking screw which holds the tongue and groove parts of the invention together. In these figures, 60 indicates a lower portion of the bit body having a tapered groove 61 therein adapted to receive a dovetail body 62 from which a bearing pin 63 extends in position to support a conical bearing body 64 for receiving a roller 65. The dovetail body 62 consists of an inner portion 66 and a smaller outer portion 67, the outer portion being of a length L, as shown in Fig. 5. In one end of the tapered groove 61 a block 70 is mounted, this block filling the cross section of the groove and being preferably secured in place by the autogenous welding method. A horizontally directed lock screw 71 passes through an opening 72 in the block 70 and the threaded forward end 73 thereof enters the dovetail body 62. The block 70 is counterbored at 75 to receive a head 76 of the screw 71, and a polygonal recess 77 is provided in the head 76 for engagement of a wrench by which to turn the screw 71. This screw 71 draws the dovetail body 62 tightly into the tapered groove 61 and holds it in this position during the operation of the bit. As shown in Fig. 6, a dovetail groove 78 may be cut in the lower portion of a bit body 80 in radial direction instead of tangentially, as previously described. The principles of the invention may be practiced in this manner, but it is not thought that the results obtained therefrom will be nearly so good as those obtained from the use of the tongue and groove interlocking means in tangential position and for the reason that the walls of the hole will serve to hold the parts in engagement should the locking screw be omitted or lost.

In Fig. 7 I show an alternative form of water course protector 82 having a flange 83 adapted to be received in a counterbore 84 of a water course passage 85 extended through a wall 86 of a bit body. The outer portion of the counterbore

84 is internally threaded, as indicated at 87, to receive a ring nut 89 having spanner wrench openings 90 therein to enable the ring 89 to be screwed down tightly against the flange 83 to hold 5 the water course protector 82.

In Figs. 1 and 2, I have shown the dovetail body 23 and the groove 24 both tapered. As a result of this design, the side walls 28 of the groove, being convergent, serve as a definite stop means for 10 preventing movement of the body 23 beyond a definite position. The resistance of the roller to the torque applied thereto from the bit body constantly forces the interlocking body 23 tightly against the stop thus provided by the converging 15 side wall 28. During the forward operation of the bit there is no actual need for the locking screw 31, as there are no forces exerted on the interlocking body, which would tend to move it out of the slot 24; therefore, there is little possibility of the bearing structure or cutter becoming lost in the well.

I claim as my invention:

1. A rotary rock bit, including: a bit body; a roller type cutter adapted for operation on said body; a bearing structure for operatively holding said cutter; and interlocking means for securing said bearing structure to said body, said interlocking means comprising cooperating parts on said body and said bearing structure adapted to slide into interengagement in a direction tangential to a circle of rotation around the axis of rotation of said body.

2. A rotary rock bit, including: a bit body; a roller type cutter adapted for operation on said body; a bearing structure for operatively holding said cutter; and interlocking means for securing said bearing structure to said body, said interlocking means comprising cooperating parts on said body and said bearing structure adapted to slide into interengagement in a direction non-parallel to the axis of said cutter and tangential to a circle of rotation around the axis of rotation of said body.

3. A rotary rock bit, including: a bit body; a roller type cutter adapted for operation on said body; a bearing structure for operatively holding said cutter; and interlocking means for securing said bearing structure to said body, said interlocking means comprising cooperating parts on said body and said bearing structure adapted to slide into interengagement in a direction substantially normal to the axis of said cutter and tangential to a circle of rotation around the axis of rotation of said body.

4. In a rock bit of the class described, the combination of: a body having a depending leg at one side thereof, said leg having an inner face; a roller adapted for operation adjacent the inner face of said depending leg; a bearing structure within said depending leg for rotatably supporting said roller; and interlocking means for securing said bearing structure to said depending leg, said interlocking means including a tongue and groove directed tangentially of a circle around the axis of rotation of said body, one of which is formed on said inner face of said depending leg, and the other of which is formed on said bearing structure.

5. A rotary rock bit, including: a bit body; a roller adapted for operation on said body; a bearing structure for operatively holding said roller; interlocking means for securing said bearing structure to said body, said interlocking means comprising cooperating parts on said body and said bearing structure adapted to slide into inter-

engagement in a direction tangential to a circle of rotation around the axis of rotation of said body, said interlocking means being tapered to provide a wedging of the parts thereof; and lock means to hold said cooperating parts of said body and said bearing structure together.

6. A rotary rock bit, including: a bit body having a pair of facing portions inclined relative to the axis of rotation of the body and forming a space therebetween; a pair of rollers each of which is adapted for operation on said body in position adjacent to one of said inclined portions on an axis substantially normal to such portion; a bearing structure for rotatably supporting each roller; interlocking means, one of which is on each of said bearing structures and the other of which is on one of said inclined portions, for securing each bearing structure to such inclined portion, one of said means comprising a groove and the other of said means comprising a tongue making interlocking engagement with said groove, said tongue and groove being slid able into engagement tangentially with respect to a circle of rotation around the axis of rotation of said body; and means for holding said interlocking means from relative movement in the direction of said tongue and groove.

7. A rotary rock bit, including: a bit body having a pair of facing portions inclined relative to the axis of rotation of the body and forming a space therebetween; a pair of rollers each of which is adapted for operation on said body in position adjacent to one of said inclined portions on an axis substantially normal to such portions; a bearing structure for rotatably supporting each roller; interlocking means, one of which is on each of said bearing structures and the other of which is on one of said inclined portions, for securing each bearing structure to such inclined portion, one of said means comprising a groove and the other of said means comprising a tongue making interlocking engagement with said groove, said tongue and groove being slid able into engagement tangentially with respect to a circle of rotation around the axis of rotation of said body and non-parallel to the axis of said bearing structure; and means for holding said interlocking means from relative movement in the direction of said tongue and groove.

8. A rock bit of the character described, including: a bit body having a pair of downwardly extending legs forming a space therebetween; a pair of roller cutter members each of which is adapted for operation adjacent the inner face of one of said legs; a supporting structure for each of said roller cutter members; interlocking means for securing each of said supporting structures to one of said legs, each of said interlocking means consisting of two parts, one of which is on the supporting structure and the other of which is on the cooperating leg, one of said parts comprising a groove and the other of said parts comprising a tongue making interlocking engagement with said groove, said tongue and groove being slid able into engagement tangentially with respect to a circle of rotation around the axis of rotation of said body; and means for holding said interlocking parts from relative movement in the direction of the tongue and groove.

9. A device as defined in claim 8, in which said tongue and groove are longitudinally tapered so as to be wedged together when in full engagement.

JAMES W. SPERRY.
